UNITED STATES PATENT OFFICE.

A. G. SHULTS AND P. M. SHULTS, OF AVOCA, NEW YORK.

IMPROVED MONEY-DRAWER.

Specification forming part of Letters Patent No. 58,490, dated October 2, 1866.

To all whom it may concern:

Be it known that we, ALEXANDER G. SHULTS and PHILIP M. SHULTS, both of Avoca, in the county of Steuben and State of New York, have invented certain new and useful Improvements in Money-Drawers; and we do hereby declare that the following is a full, clear, and exact description of the same, reference being had to the accompanying drawing, making a part of this specification, which is a vertical longitudinal section of a drawer constructed according to our invention.

This invention consists in certain novel means of opening, closing, and locking drawers designed for the safe keeping of money and other valuables in stores and other places, whereby such drawers may be much more readily and conveniently closed and locked or unlocked and opened, when desired, than those in common use, and whereby they are effectually prevented from being opened by persons reaching over or across the counter or table in which they are situated, thus rendering their contents much less liable to being stolen than has been the case with the ordinary drawers.

To enable others to understand the construction and operation of our invention, we will proceed to describe it, with reference to the drawing.

A indicates the floor, upon which is placed or secured the table, counter, or other article of furniture in which the drawer is situated, and which is marked B in the drawing. This drawer is shown at C, and is supported immediately underneath the top a of the table by suitable guides, which allow it to be pushed in or drawn out, as may be required. If desired, this drawer C may be furnished with an inner drawer or till, b, which may be capable of being moved longitudinally therein.

D is a spiral spring, which is placed behind the back or rear end of the drawer in such manner as to tend to press the drawer forward and to open the same, as will be presently set forth. This spring, instead of being spiral, as shown in the drawing, may consist of an elastic band attached to the lateral portions of the table or counter and passed around the rearmost side or end of the drawer to press the same forward in the same manner as the spiral spring just mentioned.

Situated underneath the floor A and below the table B is a pivoted lever, E, to the long or rearmost end of which is attached a weight, c, and the forward end of which is connected with a vertical sliding stem, F, which passes upward through a suitable hole in the floor, and is provided at its upper end with a knob, d.

Extending upward from the loaded end of the lever E through a suitable opening in the floor is a rod, G, which is retained in a vertical position by means of a staple, e, attached to the back of the table B.

I represents a spring-catch, which is secured upon the under side of the bottom of the drawer, and which has the under side of its rearmost end made inclined, as shown at f, in order that the said catch I may catch upon the upper edge of the forward side of a bracket, J, which is secured to the back of the table B, and is furnished at the said forward side with an inclined plate, g, which, when the drawer is pushed inward, insures the catching of the catch I upon the aforesaid edge of the bracket J, as will presently be further explained. Pivoted within this bracket is a small pulley, K, and passing over this pulley and through a suitable slot or hole, h, in the forward side of the bracket J is a cord, L, one end of which is attached to the forward part of the drawer C, and the other end of which is fastened to the rod G, as represented in the drawing.

When it is desired to open the drawer the knob d is pressed downward with the foot, and thus elevates the long or rearmost arm of the lever E, so that the uppermost end of the rod G strikes the rearmost end of the spring-catch I and raises it clear of the edge of the forward side of the bracket J, whereupon the spring D forces the drawer forward, and thus opens the same, and when the knob d is released from the downward pressure of the foot upon it the weight c of the lever E draws the rod G downward, which, acting through the cord L, draws the drawer back to its original closed position, the rearmost end of the spring-catch I sliding over the inclined plate g and catching upon the upper edge of the forward side of the bracket J, as hereinbefore set forth, and thus firmly locking the drawer, as represented in the drawing, the weight c being sufficiently heavy to overcome the outward pressure of

the spring D as the drawer is pulled back or inward, as just set forth.

Inasmuch as the knob *d* cannot be reached from that side of the table or counter opposite to that at which the said knob is situated, it follows that the drawer cannot be opened by persons reaching across the said table or counter, and the abstraction of the contents of the drawer by thieves upon the said opposite side of the counter is effectually prevented.

What we claim as new, and desire to secure by Letters Patent, is—

1. The combination of the loaded lever E and locking mechanism, or their equivalents, with the drawer C, operating substantially as and for the purpose specified.

2. The spring D, in combination with the drawer C and locking mechanism, or their equivalents, substantially as and for the purpose set forth.

3. The combination of the lever E E, rod G, spring-catch I, bracket J, cord L, and spring D with the drawer C, substantially as and for the purpose set forth.

ALEXANDER G. SHULTS.
PHILIP M. SHULTS.
